C. F. SCHWENNKER

ELECTRIC SWITCH

Filed Jan. 5, 1924

Inventor:
Charles F. Schwennker,

by Alexander S. Lantz.
His Attorney.

UNITED STATES PATENT OFFICE.

CHARLES F. SCHWENNKEE, OF SCHENECTADY, NEW YORK, ASSIGNOR TO GENERAL ELECTRIC COMPANY, A CORPORATION OF NEW YORK.

ELECTRIC SWITCH.

Application filed January 5, 1924. Serial No. 684,669.

To all whom it may concern:

Be it known that I, CHARLES F. SCHWENNKEE, a citizen of the United States, residing at Schenectady, in the county of 5 Schenectady, State of New York, have invented certain new and useful Improvements in Electric Switches, of which the following is a specification.

My invention relates to electric switches 10 and particularly to electric switches of the fluid break type which are adapted to control high potential circuits.

An object of my invention is to provide an improved construction of the operating 15 mechanism for the switch arranged so that the pressure of the gas generated by the arc formed upon opening the switch serves to accelerate the opening movement.

My invention will be better understood by 20 reference to the accompanying specification and drawing and its scope will be pointed out in the appended claims.

In the single figure of the drawing I have shown a cross section of a fluid break switch 25 of the truck type and operating mechanism therefor in accordance with my invention. In this figure the receptacle for the switch contacts comprises a casing 1 and a tank 2 containing a suitable insulating liquid, the 30 tank being secured to the casing by bolts 3 in the usual and well known manner. A pair of insulator bushings 4 each having a conductor 5 extending therethrough is shown secured to the casing 1 by means of a plate 6 and bolts 7. A suitable oil separating and 35 pressure relieving device may be connected to the opening 8 in the casing. To the lower ends of the insulator bushings 4 are attached the main and auxiliary stationary 40 contacts 9 and 10 respectively. The bridging member 11 carrying the movable contacts 12 and 13 which cooperate respectively with the stationary contacts 9 and 10 is attached to the usual operating rod 14 of insulation such as wood which rod is guided 45 in part by a frame 15 also of insulation and in the present instance shown as of wood. The upper end of the rod 14 is fastened into a cap 17 and pivoted to this cap by means 50 of the pin 18 are the two arms 19 of the bifurcated actuating lever 20. This lever is fulcrumed at 21 on a pair of links 22 pivoted at 23 to the casing 1 and connected together by a bridge 24. The rod 25 pivoted to 55 the lever 20 extends loosely through the

bridge 24 and serves to guide an accelerating spring 26. For causing the upper end of the rod 14 to move in a straight line, each arm 19 of the lever 20 is pivotally connected to the casing by a link 27 in the manner illustrated and well known in the art. The end of each arm 19 has a laterally extending flange 28 having an opening therein adapted to loosely receive the rod 29 having a head 30 on its lower end. The two rods 29 are threaded into a cross bar 32 and about the top plate 6. The cylindrical bracket 33 supported from the top plate 6 carries the flanged button 34 and a number of felt disks 35 which disks are adjustably compressed 70 by the bar 32 against the button 34. This part of the mechanism constitutes an adjustable buffer for both the up stroke and the down stroke of the switch and is described and claimed in my copending application 75 Serial No. 67,137, filed November 5, 1925, and assigned to the same assignee as the present invention.

On the side adjacent the fulcrum point of the lever 20 the casing 1 is formed with 80 the cylindrical opening 38 in which slides the piston 39. Piston 39 is pivotally connected at its inner side to the lever 20 by means of link 40 and is pivotally connected at its outer side to the operating lever 41 by 85 means of link 42. Any suitable means may be employed for operating the lever 41 as for example a solenoid or a centrifugal device, which if desired may be connected to the lever by link 43. Lever 41 is shown 90 provided with a socket portion 44 adapted to receive a stick or rod for manual operation. Inasmuch as the toggle comprising the lever 41 and the link 42 is shown adapted to take an underset position when the 95 switch is closed, suitable means obviously would be provided for maintaining the toggle in this position subject to being tripped out manually or automatically.

The operation of the switch will be readily 100 apparent from the foregoing description. To close the switch from the position shown, the lever 41 is rocked by the operating means, not shown, to the dotted line position whence movement is communicated 105 through the piston 39 and lever 20 to raise the movable contacts into engagement with the stationary contacts. In this movement the ends 19 of lever 20 are caused to move in a straight line by the links 27 and slide 110

on the rods 29. This movement is cushioned by the pin 18 in the cap 17 on the rod 14 striking against the flanged button 34 which is resiliently retained by the felt disks 35. 5 These disks have been suitably compressed previously by the cross bar 32 through which are threaded the rods 29 which abut the top plate 6. When the switch is tripped open, the tripping means not being shown, 10 the parts begin movement in the opposite direction under the influence of gravity and the accelerating spring 26. As soon as an arc is drawn between the contacts the gas pressure produced thereby acting upon the 15 piston 39 serves to assist and accelerate the opening movement. When the parts reach the full open position illustrated, further movement is checked and cushioned by the same felt disks 35 since the ends 19 of the 20 lever 20 strike the heads 30 on rods 29 which as stated above are threaded into the cross bar 32.

By the above construction it will be seen that I have provided a fluid break switch 25 of the down break type in which the operating rod does not extend through the wall of the receptacle containing the switch contacts. I have provided the receptacle with but a single opening through which the operating mechanism may be affected by the internal gas pressure and have connected the external operating mechanism to the movable contacts by means of a piston in that opening, the internal mechanism being 30 such that the piston is moved outwardly when the contacts are separated so that pressure within the receptacle tends to accelerate the opening movement of the switch. Since the operating rod 14 does not pass 35 through the top of the casing the difficulty of maintaining a gas tight joint between the rod, which is usually made of wood, and the casing is eliminated, the effective area of the piston 39 may be materially reduced and 40 in general the operating mechanism greatly simplified.

It will be apparent to those skilled in the art that my improved arrangement of operating mechanism is adapted to be used not 45 only in switches wherein the insulating fluid comprises a gas forming liquid, but is also applicable where the contacts are arranged to open in any fluid having arc extinguishing properties, whether normally in liquid 50 or gaseous form. Where an arc extinguishing gas is used which is not dissociated by any arc which may be formed at the switch contacts, the increase in pressure in the tank will be due merely to the expansion of the 55 gas due to its increase in temperature. 60 While my arrangement is such that the increase in pressure due to the arc does not tend to reclose the switch but actually accelerates the opening thereof, it is apparent 65 that the arrangement is advantageous even

in case the insulating fluid used is of such a character that the pressure in the tank is not very greatly increased when the switch is opened, since the stuffing box feature common to switches customarily used is eliminated.

While I have described only one embodiment of my invention, I do not wish to be limited to the particular form shown and described as it will be apparent that many 75 modifications therein may be made without departing from the scope of my invention as set forth in the appended claims.

What I claim as new and desire to secure by Letters Patent of the United States is: 80

1. In a fluid break switch, a receptacle comprising a cover and having an opening therein and adapted to contain fluid immersed switch contacts, a piston mounted in said opening and contact operating mechanism connected with opposite sides of said piston. 85

2. An electric switch comprising a receptacle having a cover, an insulating fluid therein, relatively movable contacts immersed in said fluid and contact operating mechanism extending from a point without to a point within said receptacle, said mechanism including a piston mounted in a wall of said receptacle and through which the 90 contact operating movement is transmitted. 95

3. An electric switch comprising a receptacle having a cover and having an opening in the side thereof, an insulating fluid in said receptacle, a stationary and a movable contact in said fluid, a piston in said opening, an operating member operatively connected to the outer side of said piston and a contact actuating member operatively connected to the inner side of said piston. 100 105

4. An electric switch comprising a closed receptacle having an opening in a side wall thereof, an insulating fluid therein, stationary and movable contacts immersed in said fluid, an operating member, and mechanism 110 for transmitting movement from said operating member through the opening in the side wall of said receptacle to said movable contact, said mechanism including means responsive to pressure within said receptacle 115 for accelerating the circuit opening movement of said movable contact.

5. An electric switch comprising a receptacle having an opening therein, an insulating fluid in said receptacle, a stationary contact in said insulating fluid, a contact adapted to be moved downwardly from said stationary contact, an operating member, means extending through the opening in said receptacle for connecting said operating member 120 with said movable contact, said means including a member slidably mounted in said opening and arranged to move outwardly of said receptacle as said contacts separate. 125

6. An electric switch comprising a recep- 130

tacle, a cover therefor, an insulating fluid therein, relatively movable contacts in said fluid and mechanism for separating said contacts, said receptacle having an opening 5 in a side wall thereof through which said mechanism extends, a portion of said mechanism comprising a piston movable in said opening and adapted to be affected by pressure within said receptacle to accelerate the 10 opening movement of said switch.

7. An electric switch comprising a casing forming a compression chamber and having a cylindrical opening in a wall thereof, a tank secured thereto, an insulating fluid

therein, a pair of stationary switch contacts 15 supported from said casing and immersed in said fluid, a pair of movable contacts mounted to move downwardly from said stationary contacts to disengage the same, an operating member exterior of said casing, a 20 lever fulcrumed intermediate its ends within said casing and operatively connected with said movable contacts, and a piston in said opening operatively connecting said operating member and said lever. 25

In witness whereof, I have hereunto set my hand this 4th day of January 1924.

CHARLES F. SCHWENNKER.
